DESIGN FOR A STOVE GRID

Harold H. Miller, Ypsilanti, Mich., assignor to
United Stove Company, Ypsilanti, Mich., a cor-
poration of Michigan

Application September 4, 1945, Serial No. 121,827

Term of patent 14 years

(Cl. D81—10)

To all whom it may concern:

Be it known that I, Harold H. Miller, a citizen
of the United States of America, residing at
Ypsilanti, in the county of Washtenaw and State
of Michigan, have invented a certain new, orig-
inal, and ornamental Design for a Stove Grid,
of which the following is a specification, refer-
ence being had therein to the accompanying
drawing, forming a part thereof, wherein:

Fig. 1 is a plan view of a stove grid showing my
new design; and

Fig. 2 is a side elevational view thereof.

I claim:

The ornamental design for a stove grid, sub-
stantially as shown.

HAROLD H. MILLER.
